SEALED ANTENNA

Bertram Trevor, Riverhead, N. Y., assignor to
 Radio Corporation of America, a corporation
 of Delaware

Application December 1, 1943, Serial No. 512,441

2 Claims. (Cl. 250—33)

1

The present invention relates to ultra-high frequency antennas, and particularly to such antennas which are so constructed as to be sealed against the effects of moisture and weather conditions.

An object of the present invention is to decrease the effect of weather and moisture on the operation of ultra-high frequency antennas.

Another object of the present invention is the provision of a weatherproof ultra-high frequency antenna.

Still another object of the present invention is the provision of a weatherproof ultra-high frequency antenna which may be readily adjusted and easily mounted on a coaxial line.

The foregoing objects and others which may appear from the following detailed description are attained by the provision of a half wave doublet radiator and a pair of quarter wave chokes all enclosed within a sealed low loss plastic case for weather protection. The case is so sealed that the entire antenna system may be maintained under a few pounds' pressure of dry nitrogen gas.

Referring now to the single figure of the drawing showing in longitudinal cross section an embodiment of the present invention, TL denotes a coaxial transmission line having an outer shell 1 and an inner conductor 2. The transmission line is adapted to be connected between the antenna and suitable transducer equipment which is not shown. The outer and inner conductors of the transmission line are cut off flush at one end. The outer shell has a coupling flange 5 soldered or otherwise hermetically attached to the end. The inner conductor 2 has an extending rod 3 soldered to its end. Rod 3 is maintained in coaxial alignment with the central aperture through coupling flange 5 by an insulating washer or button 6 inserted in the aperture of the coupling flange 5.

An outer tubular sleeve member 7 is associated with and surrounds rod 3. It carries at one end a coupling flange 9 adapted to be clamped to coupling flange 5 by means of bolts 10 and 11. The flange may be soldered or brazed as desired to tubular member 7. The apertures in flange 9 through which bolts 10 and 11 pass are preferably threaded so that flange 9 may be clamped to flange 5 without requiring the use of any clamping nuts. A hermetically sealed junction between flanges 5 and 9 is assured by the interposition of a gasket 12.

A pair of quarter wave chokes 14 and 16 are arranged to be adjustably positioned along the

2

length of tube 7. Each of the quarter wave chokes includes an outer sleeve member 18 threadedly mounted on a bushing 19. The effective electrical length of each of the chokes may be adjusted to one quarter of the operating wave length by running sleeve 18 a suitable distance onto bushing 19.

Set screws 20 and 21 are provided for locking each of the quarter wave chokes 14 and 16 in place. Once the quarter wave chokes have been located on the tube 7, an insulating button 22 is slipped over the extending end of rod 3 and clamped into position by a lock nut 24. The insulating button 22 has a shoulder on one side 15 which engages with the inner bore of tube 7 to maintain the coaxial alignment of rod 3 within tube 7.

An adjustable end portion 26 of the doublet radiator is finally screwed onto the threaded end 20 of rod 3 and is so adjusted that the overall length extending out of tube 7 is approximately one quarter of the desired operating wave length. Choke 14 is secured on tube 7 in such position that the distance from the open end of the choke to the 25 bottom of the extending quarter wave portion of the doublet is also approximately a quarter wave length. Thus, the extending portion of the doublet acts as the top half of a vertical half wave radiator, while the quarter wave portion of tube 30 7 extending beyond the quarter wave choke 14 acts as the other half of the doublet.

The distance between the open ends of chokes 14 and 16 is preferably adjusted to approximately a half wave length whereby they aid one another 35 to prevent the flow of high frequency energy along the outside of the line. Once the antenna has been adjusted to the proper dimensions for the frequency at which it is to operate, a cover including a base flange 27, a tubular sleeve 28 and 40 an end closure 29 is slipped over the antenna and clamped into position by nuts 30 and 31 engaging bolts 10 and 11. Lock washers 32, 32 are provided to prevent nuts 30 and 31 from loosening. Also, a suitable gasket 33 should be interposed between flanges 27 and 9 to assure a hermetic seal between the cover and the remainder of the system.

In order to prevent the condensation of moisture within a transmission line, it is common 50 practice to keep the line under a few pounds pressure of dry nitrogen gas. The present antenna is so designed that it may be operated in the same manner. Before the plastic cover is bolted into place, a dry nitrogen tank may be connected 55 through an appropriate fitting (not shown) to

the coaxial line and nitrogen allowed to flow through the line until the air within the line and antenna has been replaced.

Small apertures 36 are provided in each of the insulating spacers 6 and 22 to permit the flow of gas through the system. As soon as it has been determined that dry nitrogen is issuing from the antenna end of the system, the plastic cover is bolted into place and the desired pressure built up in the line. Since the antenna system is as hermetically sealed as the remainder of the line, the desired pressure will be maintained with substantially no loss.

While I have illustrated a particular embodiment of the present invention, it should be clearly understood that it is not limited thereto since many modifications may be made in the several elements employed and in their arrangement, and it is therefore contemplated by the appended claims to cover any such modifications as fall within the spirit and scope of the invention.

Having now described my invention, what I claim as new and desire to have protected by Letters Patent is:

1. An antenna system including a section of coaxial line including an outer shell and an inner conductor, said inner conductor extending from one end of said outer shell a distance equal to approximately one quarter of the operating wavelength, the other end of said outer shell bearing a coupling flange for hermetic connection to a further coaxial transmission line, a tubular insulating casing closed at one end and carrying a coupling flange at the other end, and coaxially arranged with respect to said outer shell, said

outer shell and inner conductor being maintained in coaxial relationship by insulating spacing washers, said spacing washers having perforations therein to permit the flow of a fluid from said further coaxial line between said outer shell and said inner conductor and between said outer shell and said casing, and means for clamping the coupling flange of said casing in a fluid-tight relationship to the coupling flange of said outer shell.

5 2. An antenna system as set forth in claim 1 in which a pair of quarter wave traps are so arranged along said outer shell within said insulating casing as to prevent the flow of radio frequency energy along the outside of said shell.
